W. G. HALL

JUICE STRAINING SYSTEM FOR SUGAR CANE MILLS

Filed Jan. 29, 1926

UNITED STATES PATENT OFFICE.

WILLIAM G. HALL, OF HONOLULU, TERRITORY OF HAWAII.

JUICE-STRAINING SYSTEM FOR SUGAR-CANE MILLS.

Application filed January 29, 1926. Serial No. 84,658.

The invention relates to a juice straining system for sugar cane mills and has for its object to provide a simple and effective straining apparatus, preferably located in the bottom of the boot of the conveyor between the crusher and the shredder of a standard mill, the strainer discharging the clear juice into a receptacle, which, in turn, is connected by suitable piping for delivering the juice directly to the boiling house.

The invention is illustrated in the accompanying drawing, in which:—

The figure is a diagrammatic side elevation of a standard mill showing the means for delivering the mixed juice from the several roller units, as well as the juice expressed by the crusher, directly to the strainer.

Referring to the drawing, 1 indicates a standard crusher for crushing or breaking cane, which is then carried by an endless flight conveyer 3 to a shredder 6 whence it is delivered by a conveyer 7 to the first roller unit 10 of the mill train. As indicated, there are four roller units 10, 10', 10² and 10³, successively connected by intermediate conveyers 20, 20', and 20². Each of the roller mill units discharges the expressed juice into the pan 11, 11', 11² and 11³, respectively. The pans 11 and 11' below the first and second roller units are connected by discharge pipes 12 and 12' to the pump 13, which, in turn, is provided with a single discharge pipe 14. The pans 11² and 11³, below the third and fourth mills, are connected by pipes 12² and 12³ with the pump 13', which latter is provided with two discharge pipes, the first of which 14' discharges the juice into a maceration distributor 15 located above the first intermediate conveyer 20 and discharge pipe 14² delivers the juice into a similar maceration distributor 15' above the intermediate conveyer 20'. A suitable water distributing pipe 25 is located above the last intermediate conveyer 20² for supplying the necessary maceration to the bagasse on said intermediate conveyer. By this particular arrangement for distributing the juice expressed by the several roller units, which is generally known as mixed juice, the latter is ultimately received by pump 13 and delivered by discharge pipe 14 leading from said pump and it is the purpose of this in-

vention to provide an effective straining device for removing the cushion and other solid material from the mixed juice, and at the same time effectively straining the larger proportion of the juice, which is expressed from the cane by the crusher 1. In order to effect these desired results, the boot or closed casing 2 of the conveyer 3 interposed between the crusher 1 and the shredder 6 is provided at its lower end with a screen 26, which conforms generally to the shape of the bottom or lower section of the boot and is engaged by the slats or scraper elements usually associated with the conveyer 3. Secured to or forming a part of the boot or casing of the conveyer adjacent screen 26 is a receptacle 27 into which the juice passing through the screen is discharged, which receptacle is provided with an outlet 28 adapted to be connected with piping leading to the boiling house. The discharge pipe 14 of pump 13 is also connected with the lower end of the boot of the conveyer 3 and discharges the mixed juice directly into the lower end of the boot above the screen, so that all of the juice, to wit, that extracted by the crusher 1 and the mixed juice from the several roller units of the mill is discharged directly into the boot of the conveyer 3 and passes freely through the screen 26, leaving the cushion, broken cane and other solid material on the screen whence it is removed by the slats or scrapers of the conveyer flight, so that the openings in the screen are maintained free and unobstructed. All of the strained juice passes directly into the chamber 27 whence it is delivered practically free from all solid matter by way of the discharge 28 to the boiling house.

By means of this relatively simple, but highly effective screening arrangement, all of the juice extracted from the mill is immediately strained and delivered to the boiling house and is not subjected to danger of inversion or contamination, such as is likely to occur with the more complicated strainer devices heretofore employed.

What I claim is:

1. The combination of a sugar cane mill including a preliminary crusher and an elevating conveyor having a casing for delivering the cane from the crusher to the first mill unit, a strainer in the bottom of the casing, a receptacle into which the strainer dis-

charges, and means for delivering the mixed juice from the mill units to the casing above such strainer.

2. Means for straining the juice from a sugar cane mill which includes a preliminary crusher for the cane, several mill units and an elevator provided with an enclosing boot for delivering the cane to the first mill

unit; comprising a strainer in the bottom of said boot, a receptacle into which the strainer discharges, and means for delivering the mixed juice from the several mill units to said boot above the strainer.

In testimony whereof I affix my signature.

WILLIAM G. HALL.
